UNITED STATES PATENT OFFICE.

EZECHIEL WEINTRAUB, OF LYNN, MASSACHUSETTS, ASSIGNOR TO GENERAL ELECTRIC COMPANY, A CORPORATION OF NEW YORK.

ELECTRIC LAMP.

1,086,107.

Specification of Letters Patent.

Patented Feb. 3, 1914.

Original application filed February 26, 1902, Serial No. 95,662. Divided and this application filed May 14, 1910. Serial No. 561,293.

To all whom it may concern:

Be it known that I, EZECHIEL WEINTRAUB, a citizen of the United States, residing at Lynn, in the county of Essex, State of Massachusetts, have invented certain new and useful Improvements in Electric Lamps, (being a division of my application filed February 26, 1902, Serial No. 95,662,) of which the following is a specification.

10 The invention which I have hereinafter described and claimed relates to methods of producing light by electricity and to certain improvements in electric lamps of that type in which electrical energy is converted 15 into light through the medium of vaporous or gaseous matter maintained in a luminescent condition by the electric current. In an application filed concurrently herewith, I have described and have claimed broadly 20 certain features of invention whereby a lamp of this character may be started into operation, together with other correlated features unnecessary here to mention.

In the present application I propose to 25 disclose certain arrangements for securing automatic operation of the lamp, the novel features of which arrangements will be pointed out in the following specification, in which—

30 Figure 1 represents one embodiment of my invention, Fig. 2 a modified detail and Fig. 3 a different form of the invention.

I will premise my description of these 35 detailed arrangements by stating that in lamps of the general character mentioned, various difficulties and disadvantages have heretofore been attendant upon the means employed for starting the arc. The usual method of starting, of which of course there 40 are various modifications, is to impress upon the terminals of the lamp, for a certain period or periods, a high electromotive force, many times greater in value than the normal electromotive force at which the 45 lamp is intended to operate. This starting electromotive force apparently operates to break down the high initial resistance between the electrodes of the lamp whereupon the lamp starts.

50 My present invention, among other valuable features, provides means operating automatically upon turning on the current whereby a lamp of the type mentioned will

electromotive force no greater than that impressed upon the lamp circuit by the supply mains. The starting is performed by producing locally within the lamp ionized vapor which, by the migration of its ions or by some other operation the nature of which is not known with certainty, permits the application of the normal voltage to the terminals of the lamp to start the lamp into operation. After the lamp has been started, the supplemental or auxiliary source of ionized vapor may be cut out of circuit and to perform this function as well as to initiate automatically the production of ionized vapor, I may make use of the arrangements shown in the drawings above referred to.

Referring to Fig. 1, the lamp will be seen to consist of a main tube 1 of indefinite length, indicated by the dotted lines 2. At either end of the lamp are electrodes, the lower electrode consisting in the present instance of a body of mercury filling a narrow downward extension 4 of the lamp and also a small portion of the main body of the tube as indicated. In the upper portion of the tube is located the other main electrode, 75 consisting of a somewhat bell-shaped body 7 of suitable material as metal or graphite. This electrode communicates through a sealed-in wire 8 with a body of mercury 9 contained in an exhausted chamber 10 out 80 of which extends a wire 11 sealed through the walls of the chamber, the projecting end 85 of the wire forming one of the external terminals of the lamp.

The lamp itself is exhausted to as high a 90 degree of vacuum as possible, the process of preparing and evacuating a lamp being set forth in the application above referred to, which process however forms no portion of the invention claimed herein. That the 95 vacuum thus produced may be maintained in as perfect a condition as possible, the electrode 7 is connected with the exterior terminal 11 through the evacuated chamber 10 as a precautionary measure.

100 Communicating with the main tube 1 is a chamber 12 of somewhat cylindrical shape, the lower end of which is contracted as at 13 and filled with mercury up to the level sufficient to cover the connecting neck 14 of the tube and thereby afford electrical connection between the body of mercury 3 in

municating chamber 12. Within the chamber 12 is mounted a body of magnetic material consisting in this instance of a rod or a bunch of iron wires 15 contained within a glass tube 16 from which the air has been exhausted. Located within proper relation to this iron rod or bunch of wires is a solenoid 16' which, when energized, is adapted to withdraw the tube containing the iron core to a greater or less extent out of the mercury in which it is partially immersed. In order that the movements of this tube within its inclosing chamber shall not endanger the walls of the chamber, the tube is provided at its ends with springs 17-18 adapted to serve as buffers. In order to render the displacement of the tube 16 as great as possible, the spaces between the iron and the tube may be filled with mercury.

20 Current may be supplied to the lamp from a suitable source of current, and connection therewith may be made by mains indicated at 19 and 20. One of these mains, as the main 19, may be connected to the lower terminal 5 of the lamp, while the other main 20 through a switch 21 may be connected to the upper terminal 11 of the lamp. The lead extending from the switch 21 is connected through the fixed contacts 22 and 23 of a cut-out apparatus 24 to a sealed-in terminal 25 of the lamp which terminal communicates with the mercury in the tubular chamber 12 and forms an auxiliary or supplemental electrode for the lamp, the terminals 5 and 11 acting as the main terminals during operation.

In series with the circuit between the main 20 and the auxiliary terminal 25 is the solenoid 16' and a current limiting resistance 26. The main terminal 11 of the lamp is connected to the same supply lead as the auxiliary terminal 25 and the conductor forming this connection includes therein a resistance 27 and the solenoid or magnet 28 of a cut-out device 24, which magnet acts upon a core 29 carrying a bridging contact adapted when no current flows in the solenoid or magnet to bridge over the fixed contacts 22 and 23, and to break this bridging connection when current does flow in the magnet or solenoid.

In the operation of starting the lamp, the switch 21 may be closed, thereby first causing current to pass through the solenoid 16' and through the body of mercury in the lamp to the other terminal of the source of current. The resulting current, which is limited in value by the resistance 26, causes the tube 16 to be lifted out of the mercury by the action of the solenoid 16', thereby lowering the level of the mercury and opening the circuit through the same at or about the point 30. The resulting arc or discharge which takes place causes a liberation of mercury ions which operate to set up the

flow of current through the main tube between the main electrodes of the lamp. As soon as this current commences to flow, the cut-out device 24 operates and interrupts the branch current initially flowing into the lamp at the terminal 25 and maintains the same out of circuit until the main current is for any reason interrupted, whereupon the operation above described is repeated.

Instead of inclosing the iron constituting the armature or core of the solenoid 16' in a glass tube, it may be arranged as shown in Fig. 2, to be movable longitudinally of a guiding tube 31 located as shown within the chamber 12. Both ends of the armature 30 may be provided with buffer springs indicated at 32 and 33. The guiding tube 31 has a small opening 34 communicating, above the surface of the mercury, with the chamber 12 whereby its contents may be evacuated when the evacuation of the main tube takes place.

In Fig. 3 is shown a different arrangement for securing an automatic starting of the lamp. In this case the lower main electrode 90 consists as before of a body of mercury 34 while the supplemental electrode likewise consists of a body of mercury 35. The level of the mercury of these two electrodes is such however that the mercury does not quite bridge over the space between them but leaves a gap as at 36. Carried by the tube in any suitable manner is a body of magnetic material 37 in cooperative relation to which is mounted a solenoid 38. 100 This solenoid is connected in a circuit between one of the supply mains 20 and the supplemental electrode 35. A resistance 39 connects the electrode 35 with the other supply main 19. When the main switch 40 is closed, the solenoid 38 attracts its core 37 carried by the lamp which may be suspended by the ring 41 or otherwise so that it may swing. With proper adjustment of parts the motion produced by the solenoid 38 causes a momentary flow of the mercury between the electrodes 34 and 35 so as to connect the same, which flow, as it recedes, opens the circuit between the electrodes and springs an arc, setting free the ionized mercury vapor which operates to start up the main tube. As soon as the main current commences to flow, a cut-out 42, arranged and connected like the cut-out 24 in Fig. 1, opens the circuit of the solenoid 38 and renders the same inactive until the current through the lamp ceases to flow, whereupon if the switch 40 still be closed to the mains the operation above described is repeated.

In the lamps which I have above described, the electrodes at the upper end of each lamp, as represented at 7 in Fig. 1 and at 43 in Fig. 3, may be made of any one of a number of different materials such as iron or graphite. Of these I prefer the latter 130

since it does not readily occlude gases, or, if it does, then it readily gives them up; nor does it, when heated, undergo chemical change such as to generate gases, thereby 5 impairing the vacuum of the lamp.

Although the automatic cut-out to which I have heretofore referred may be used or not, as desired, to interrupt the supplemental or auxiliary circuit, it need not 10 always, when used in this connection, be arranged to interrupt the circuit but may, under certain conditions, be employed to vary the resistance of this circuit by opening or closing a short circuit about a portion 15 or all of the resistance in this supplemental circuit; and further it may, if desired, be adjusted so as to perform these functions at any selected current value. Thus if it is desired to run current in the 20 main tube at a low value, for example, the cut-out may be arranged so as to short-circuit a portion of the resistance in the supplemental circuit, thereby increasing the current flow therein and so maintaining 25 stable operation of the lamp at the selected low current value. Or it may be adjusted to reduce the supplemental circuit current when the main arc starts, as when the main arc is in operation the supplemental arc will 30 run on lower current.

What I claim as new and desire to secure by Letters Patent of the United States is:

1. The combination of a vapor apparatus supported so as to swing or oscillate, magnetic means for oscillating or swinging said 35 apparatus, and electrodes in said apparatus

adapted to be brought into engagement or separated by the swinging or oscillating movement.

2. A mercury vapor apparatus comprising an exhausted container, electrodes therein adapted to be alternately connected and disconnected within the container by good conducting material, and electro-magnetic means adapted to move the said container 45 and thereby initiate a flow of current through the mercury vapor.

3. A mercury vapor device comprising a movable container for mercury, electrodes therein, said container being adapted to 50 occupy either of two positions in one of which positions it is held by gravity, and automatic means brought into action by current flow for tilting the device into the other position, whereby metallic connection 55 between the electrodes is alternately made and broken.

4. A mercury vapor apparatus comprising an exhausted container, electrodes therein adapted to be alternately connected and 60 disconnected within the container by good conducting material, and automatic means adapted to move said container and thereby initiate a flow of current through the mercury vapor. 65

In witness whereof, I have hereunto set my hand this 12th day of May, 1910.

EZECHIEL WEINTRAUB.
